UNITED STATES PATENT OFFICE

YSAUNO GÓMEZ, OF BALLINGER, TEXAS

PLOW

Application filed April 8, 1929. Serial No. 353,457.

My present invention has reference to a new and novel plow construction which is primarily in the nature of a lister or riding middle breaker and among the objects 5 of the invention is the provision of a plow construction in which the bottom or shovel may be tilted or canted upon its standard support to engage in different depths of soil, one in which the plow lift includes a 10 rack surface on the standard which is engaged by a lever operated toothed wheel, so that the plow may be easily and quickly adjusted with respect to the frame thereof and positively held when adjusted; one in which 15 a hitch shift of a new and novel arrangement is provided, the same including means for imparting an angular movement to one of the wheels of the machine and to simultaneously impart a similar movement to the 20 clevis to arrange the same in the same direction as that of the wheel, so that the plow will be positively directed at varying desired angles or when the same is to make its return movement over the field, and further one in 25 which the operating means for all of the parts are in close proximity to the driver's seat, which latter is also adjustable on the beam of the plow.

To the attainment of the foregoing the invention consists in the improvement hereinafter described and definitely claimed.

In the drawings:

Figure 1 is a top plan view of a plow constructed in accordance with this invention.

Figure 2 is a side elevation thereof with parts in section.

Figure 3 is a substantially vertical longitudinal sectional view through the improvement.

Figure 4 is a rear elevation thereof.

Preferably my improved plow construction is entirely constructed of metal which enhances the sturdiness and stability thereof and the ground or traction wheels of the improvement are indicated by the numeral 1. 45 Each of the wheels 1 is journaled on the spindle end of an axle. From its spindle each of the axles is extended downwardly, as at 2, and from thence bent inwardly and extended upwardly, as at 3. Thus the lower

portion of each of the axles is U-shaped or cranked.

The plow beam is indicated by the numeral 4. The beam passes between the spaced lower plates 5 of the standard. The 55 upper portion of the standard is fixedly secured between the plates 5 and is for distinction indicated by the numeral 6. This portion of the standard is provided with teeth 7, and, therefore, is in the nature of a rack. 60 The beam is fixed between the plates 5 of the standard, and the beam has secured to the sides thereof rearwardly directed plates 8 that have their ends formed with eyes 9 that provide guides through which the vertical 65 inner portions 3 of the axles pass.

There is arranged between the spaced plates 5 or what may be termed the bifurcated lower portion of the standard a curved tongue 10 which is pivotally secured to the 70 standard, as at 11 and which has an angle rearwardly extending lower portion in the nature of a runner 12. The tongue, at its juncture with the runner, is formed with an extension that has its outer end divided to 75 provide the same with what I will term angularly directed ears 13 and these ears are loosely pivoted, as at 14, to the sides or molds of the plow bottom or shovel 15.

The mold sides of the shovel are formed 80 with ring extensions 16 and a tongue 17 which is arranged therebetween. There is passed through this tongue and the tongue or the angle extension 10 of the runner 12 the shank of a headed bolt 18. There are washers between the head of the bolt 18 and the rear edge of the rounded and bifurcated end 5 of the standard 6, one of said washers, indicated for distinction by the numeral 19, contacting with the said rear edge of 85 the standard. Arranged around the shank of the bolt and having one of its ends contacting with the washers 19 and its other end contacting with an outer washer 20 there is a coil spring 21. There is screwed 90 on the end of the bolt 18 a nut 22 which engages with the washer 20 and thereby regulates the tension of the spring 21.

The upper end of the tongue extension 10 of the runner 12 is rounded and formed with 100

teeth 23 which are in mesh with the teeth of a wheel 24 whose shaft 25 is journaled in suitable bearing openings in the plates 5 of the standard. The shaft 25 has one of its ends offset and formed with an extension in the nature of a lever 26, the said lever having fixed thereon a transverse plate 27 that provides a gripping surface for the foot of the operator of the plow.

10 The rear end of the beam 4 is slightly rounded downwardly, and has secured there-around a substantially U-shaped clip 28, the securing means for the clip being in the nature of a removable element such as a 15 bolt engaged by a nut. The clip receives therein the lower end of a curved spring support 29 for the driver's seat 30. Arranged along the sides of the beam 4, inward of the clip 28, there are plates 31, and 20 passing through and connecting the ends of these plates there are adjustable means, broadly indicated by the numerals 32, the said means being preferably in the nature of bolts which are engaged by nuts. By 25 this arrangement it will be noted that the supporting spring 29 for the seat 30 may be adjusted to bring the seat toward or away from the beam and likewise by this means it will be noted that the seat 30 may be 30 adjusted longitudinally on the beam.

As far as the description has progressed it will be obvious that a pressure of the foot of the rider upon the lever 26 will cause the turning of the toothed wheel 24 and 35 the said toothed wheel engaging with the teeth or rack on the end of the tongue or extension of the runner 12 will tilt or cant the plow bottom or shovel 15 upon the pivot 11 so that the point of the plow may be 40 raised to a determined degree, a release of pressure upon the lever permitting the spring 21 to return the plow bottom or shovel to its initial position.

The vertical members or extensions 3 of 45 the axles are each guided through a pair of spaced eyes or bearings 33 formed on the ends of plates 34 provided on the ends of a bar 35. The plates 34 and their bearing portions 33 may be in the nature of substantially 50 U-shaped brackets which are bolted or otherwise fixed to the bar 35 but the said elements 34 and 33 may be integrally formed with the bar. The bar and the ends thereof are really in the nature of 55 a frame, and the central portion of the said frame is integrally formed with an upstanding member 36 that is provided with spaced outwardly extending arms 37. Thus the projection 36 is in the nature of a bifurcated 60 member and receives therethrough and provides a guide for the non-toothed face and sides of the rack extension of the standard. There is journaled between the side members 37 of the projection 36 a shaft 38 which 65 has fixed thereon a toothed wheel 39 that

is in mesh with the teeth of the rack 7. One end of the shaft 38 may be bent or may have secured thereto a rearwardly extending lever 40. The lever, however, is preferably 70 removably secured to the shaft, and the connection therebetween is rather loose being sufficient to permit a slight lateral movement of the lever in order to bring the same into or out of notches 41 provided in an arched rack 42 which is fixed on one of the 75 parts 38 of the element 36. The lever 40 has an offset end 43 providing a grip for the hand of the occupant of the seat 30 and by this arrangement it will be seen that a swinging of the lever will cause the turning 80 of the toothed wheel 39 which engages with the rack 7 and consequently a vertical adjustment of the standard and the plow bottom carried thereby with respect to the beam 4.

85 In this manner it will be seen that the plow bottom or shovel may be properly regulated with respect to the depth of the furrow to be made thereby and also by this arrangement it will be seen that the shovel may be raised above the ground surface 90 when the plow travels over a field before being brought to operative position.

To more effectively reinforce the standard with respect to the beam there is pivotally connected to these elements angle 95 braces 44.

The extension 3 of one of the axles is fixed in its bearings 33-33 but the extension 3 of the second axle may be turned in 100 its bearings 33. This last mentioned extension 3 has fixed thereon a sleeve 45 that rests on the upper face of the lower bearing 33, the upper face of the said sleeve being roughened for coengagement with the 105 roughened under face on one end of a lever 46. Surrounding the extension 3 and exerting a pressure between the upper bearing 33 and the said end of the lever there is a 110 coil spring 46'. Obviously the lever may be otherwise connected with the sleeve 45. The lever has a widened or laterally extending portion 47 provided with an arcuate slot 48 through which the plate 34 passes. The upper end of the lever is formed with an angle 115 extension in the nature of a hand grip 49. The under face of the lever may be provided with a tooth or the said lever may be received in notches 50 provided in an arched 120 rack 51 that is fixed to the body member 35 of the frame. The inner end of the lever 46, at the portion thereof through which the shaft extension 3 passes has an extension 52 which is bent upwardly and from thence 125 inwardly forming this end of the lever with what may be termed an arm.

There is pivotally secured to the outer end of the arm 52 the bifurcated end of a link 53. The link is arranged angularly 130 over the beam 4, and the second or free end

of the link is pivotally connected to one end of a centrally pivoted rocker member or arm 54. The rocker arm has its pivot 55 received in an upstanding lug 56 on the beam 4. The second end of the rocker arm 54 has pivotally connected thereto one of the bifurcated ends of another link 57. This link is forwardly directed and is normally arranged in a plane with the beam. The second bifurcated end of the link 57 is pivotally secured to the inner and angle end 58 of a clevis 59. The clevis is pivotally secured, as at 60, to the outer end of the beam 4 or rather to a bearing member which is fixed on the said outer end of the beam. By this arrangement it will be noted that when the lever 46 is shifted one of the ground wheels 1 will be turned angularly with respect to the frame of the device and by virtue of such turning the rocker arm 54 will be swung by the link 53, and consequently the link 57 will swing the clevis 59 in the same direction and to the same angle as that assumed by the ground wheel 1. The lever 46 engaging in one of the notches 50 in the rack 51 will hold the said wheel and the clevis at desired angle positions with respect to the remainder of the construction, and by this simple means it will be seen that I have provided a hitch shift which not only changes the line of draft of the plow but incident to the turning of the ground wheel will automatically cause the draft animals or the tractor by which the plow is drawn to assume a proper position for pulling the said plow.

It is believed that the construction, operation and advantages of my improvement will be understood and appreciated by those skilled in the art to which the invention relates when the foregoing has been carefully read in connection with the accompanying drawings but obviously I do not wish to be restricted to the precise details herein set forth and, therefore, hold myself entitled to make such changes therefrom as fairly fall within the scope of what I claim.

What I claim is:—

An agricultural implement comprising a wheel supported frame, a beam connected with the frame, a standard connected with the beam, said standard having a bifurcated lower part, a plow having a rearward extension which passes between the lower end of the bifurcated portion, means for pivoting the extension in said bifurcated part, a bolt passing through an upper part of the plow and through the bifurcated portion, a spring on the rear of the bolt and bearing against the rear edge of the beam and the nut on the bolt, said extension having an upwardly extending part arranged between the members of the bifurcated portion of the standard, with teeth on its upper end, a pinion carried by the standard and engag-

ing the teeth and a foot actuated member connected with the pinion for rotating the same whereby the plow will be tilted upwardly or downwardly when the foot engaging member is actuated.

In testimony whereof I affix my signature.

YSAUNO GÓMEZ.
